(57) **CLAIM**

The ornamental design for a pot lid, as shown and described.

DESCRIPTION

FIG. 1 is a front perspective view of a first embodiment of a pot lid showing my new design.

FIG. 2 is a front view thereof.

FIG. 3 is a rear view thereof.

FIG. 4 is a left side view thereof.

FIG. 5 is a right side view thereof.

FIG. 6 is a top side view thereof.

FIG. 7 is a bottom side view thereof.

FIG. 8 is a section view at Y-Y of FIG. 4 thereof.

FIG. 9 is a section view at X-X of FIG. 2 thereof.

FIG. 10 is a section view in used state thereof.

FIG. 11 is a section view in another used state thereof.

FIG. 12 is a front view of a second embodiment of a pot lid showing my new design.

FIG. 13 is a rear view thereof.

FIG. 14 is a left side view thereof.

FIG. 15 is a right side view thereof.

FIG. 16 is a top side view thereof.

FIG. 17 is a bottom side view thereof.

FIG. 18 is a section view at Y-Y of FIG. 14 thereof.

FIG. 19 is a section view at X-X of FIG. 12 thereof.

FIG. 20 is a section view in used state thereof; and,

FIG. 21 is a section view in another used state thereof.

The broken lines in figures show portions of the pot lid and environment that form no part of the claimed design.

1 Claim, 9 Drawing Sheets
